UNITED STATES PATENT OFFICE

2,098,896

SALES TAX REGISTER

Charles H. Whitacre, Morgantown, W. Va.

Application July 1, 1935, Serial No. 29,358

1 Claim. (Cl. 235—100)

The present invention consists of a sales tax register adapted for the reception of coins of different denominations.

In the present invention, I utilize apparatus of simple construction which automatically operates by gravitation of the coins deposited in the register, the latter being sealed to prevent tampering.

In states which have levied sales taxes, a burden is imposed upon merchants in keeping an accurate record of the taxes due the Government on the sale of commodities which have been taxed, especially where the commodities are sold in large quantities and the tax is small. It is, therefore, the object of my invention to provide a suitable registering mechanism in conjunction with a receptacle for the tax coins whereby an immediate record is made of the collection of the tax upon the consummation of the sale, the registering mechanism being suitably sealed and the coin receiving portion of the register freely accessible to permit the coins to be removed with facility, without in any way disturbing the registering mechanism.

Other objects of the invention will be apparent from the following description of the present preferred form of the invention, wherein:—

Fig. 1 is a perspective view of a sales tax register constructed in accordance with the present invention.

Fig. 2 is a vertical sectional view of the register showing to advantage the registering mechanism of the present invention, and also showing to advantage the coin receiving compartments in the bottom of the register.

Fig. 3 is a vertical sectional view taken on the line 3—3 of Fig. 2 looking in the direction of the arrows, showing the registering mechanism in end elevation together with the spring lock which normally holds said mechanism from movement.

Fig. 4 is a detail enlarged fragmentary sectional view taken on the line 4—4 of Fig. 3, looking in the direction of the arrows, showing the registering mechanism in top plan, and

Fig. 5 is a perspective view of one of the spring locking arms of the present invention.

The register of the present invention consists of a housing generally designated 6, the housing including a base 7 upon which is superimposed a casing 8, one end of which is adapted for the reception of a coin receiving till or drawer 9, the latter being divided into compartments by partitions 10. The till or drawer 9 may be equipped with a hand hold 11 to facilitate sliding movement of the drawer in the casing. Rising upwardly from the top of the casing

8 is a cover 12 which, by preference is fixedly secured to the top of the case 8 and recedes from the margins of the latter. The front of the cover is provided with an opening 13, across which a transparent panel 14 of Cellophane, glass, 5 mica or other suitable material is secured, as illustrated to advantage in Figs. 3 and 4.

Mounted on top of the casing 8 and extending upwardly within the cover 12 and through the upper wall of the latter is a coin chute 15. In 10 the present instance, the chute is formed from a sheet of metal, the free ends of which are fixedly engaged to the casing, while the intermediate portions of the sheet are arranged in parallel relation and spaced by bars 16. Between the 15 bars 16, a series of coin passageways 17 are provided, each of which registers with a complementary opening 18 formed in the top of the casing 8 so as to place the coin passageways in communication with the compartments of the 20 drawer or till 9. The front wall of the chute 15, above the cover 12, is provided with a plurality of circular openings 19 of a size complementing coins which are adapted to be urged therethrough. Each of the openings 19 communicates with the coin passageway 17, consequently coins which are passed through the opening 19 will gravitate through the passageway 17, the opening 18 and into the drawer 9.

It is the purpose of this invention to provide 30 suitable means to interrupt the passage of coins through the chute, said means consisting of registering mechanism, generally designated 20, and the other means consisting of a lock, generally designated 21, which cooperates with the registering mechanism in a manner more fully hereinafter described.

The registering mechanism consists of any 40 standard type of register of the cyclometer type, such as indicated in the drawings at 22. Each of the registering elements 22 is secured to the chute 15. Preferably, each of the elements 22 includes a plate 23, which carries bolts 24, the latter having their free ends passed through the chute and partitions 16 as illustrated to advantage in Fig. 4. 45 The elements 22, are spaced from the chute by suitable spacing sleeves 25 so as to center said elements. When so positioned the elements 22, are arranged directly in back of the transparent panel 14 so that the numerals of each cyclometer 50 are clearly legible through the panel.

Each of the cyclometers 22 is provided with an axial shaft 26, the free end of which carries a wheel 27. Each of the wheels 27 includes a plurality of radial spokes 28, the free ends of which 55

intersect one of the passageways 17 when the wheel is rotated. Consequently, a coin passing through the chute will contact a spoke of the wheel 27, causing movement of the latter and correspondingly operating the cyclometer 22.

It is necessary that the wheels 27 be held in a predetermined position so as to positively intercept coins passing through the chute and I have for this purpose provided the locking means 21. This means in the present instance consists of an arm or bar 29, one end of which carries a resilient plate 30. As shown in Fig. 5 of the drawings one extreme end of the plate 30 is secured to an extreme end of the bar or arm 29, while the opposite extreme end of the plate is anchored to the chute 15, by an angle bolt 31. Each of the angle bolts 31 extend through the chute and one of the bars 16, the opposite ends thereof projecting upwardly through the top wall of the cover 11 and secured to the latter by jam nuts 32. The upper outer end of each of the bolts is provided with an opening into which a sealed connection 33 is mounted, it being necessary to break the seal before one of the nuts 32 can be removed from the bolt. In this way possibility of tampering with the mechanism is reduced to minimum. The opposite ends of the arm or bar is formed to provide a detent 34 adapted to ride over the hub of a wheel with which it is engaged and to move into openings formed in the hub at the base of the spokes 28. In this manner, the wheel is locked from movement. Each of the bars or arms 29 is also provided with a finger 35, the free end of which is beveled as indicated at 36, and normally rests in one of the coin passageways 17 of the coin chute. The location of the beveled end of the finger is just above its wheel spoke, whereby a coin passed

through the chute will first engage the finger 35 so as to urge the detent 34 out of engagement with the wheel hub immediately following which the coin engages a spoke of the wheel. This rotates the wheel until the next opening in the wheel hub reaches the zone of the arm detent 34, which latter falls into said opening under the spring pressure of the bar or arm 29.

I have shown a recorder adapted for coins of three denominations and have provided coin passageways for the coins of each denomination, also a registering mechanism for the coins of each denomination, and a locking means for the coins of each denomination, as well as a separate coin compartment in the till 9. It is, of course, to be understood, however, that the number of these may be increased or diminished without departing from the spirit of the invention. It is furthermore to be understood that various changes may be made in the details of construction, proportion, and arrangement of parts within the scope of the claim hereto appended.

What is claimed is:—

A register including a housing provided with a coin chute, a wheel rotatably mounted in the housing, the wheel including spokes the free terminals of which project into the coin chute, a bar one end of which issues into a resilient plate attached to the chute, the opposite end bearing in yieldable engagement with said wheel to normally secure the latter from movement, a member on the bar extending into the chute to be engaged by a coin passing through said chute to release the bar from engagement with said wheel, and means driven by the wheel to register when the wheel moves under the weight of the coin.

C. H. WHITACRE.
